UNITED STATES PATENT OFFICE.

FINIS E. ROACH, OF CHICAGO, ILLINOIS.

AUTOMATIC REGULATING MEANS FOR FURNACES.

No. 825,615.

Specification of Letters Patent.

Patented July 10, 1906.

Application filed September 29, 1904. Serial No. 226,449.

To all whom it may concern:

Be it known that I, FINIS E. ROACH, a citizen of the United States, and a resident of the city of Chicago, in the county of Cook and State of Illinois, have invented certain new and useful Improvements in Automatic Regulating Means for Furnaces; and I do hereby declare that the following is a full, clear, and exact description of the same, reference being had to the accompanying drawings, and to the letters of reference marked thereon.

This invention relates to automatic regulating means for furnaces, and more particularly to means for automatically regulating and controlling the intensity and duration of the heat of the furnace.

With many kinds of furnaces it is desirable to gradually increase the heat to a maximum temperature, at which the furnace is held for a period of time dependent upon the use to which the furnace is to be put and afterward to shut off the heat to permit the furnace to cool. Various forms of furnaces are used in this manner, and heretofore with dental furnaces the operator applies the heat gradually—as, for instance, in baking porcelain—until the proper temperature is secured and to which the porcelain is subjected for one or more minutes, after which the furnace is allowed to partially cool and the bake is removed. During the entire period the operator must give constant attention to the operation of the furnace and the condition of the material to be treated therein, and failure to promptly reduce the heat of the furnace or remove the article at the proper moment results in the porcelain or other material treated being ruined.

The object of this invention is to provide means for automatically regulating and controlling furnaces of any kind, both as to the degree of heat to be attained and the length of time to which the object treated shall be subjected to the heat.

Inasmuch as the temperature and time required for properly treating a given substance are usually known or may readily be determined by experiment, it is a further object to provide mechanism adapted to be set to a given time and acting to regulate and control the furnace perfectly, thus dispensing with the care and attendance of the operator.

The invention is shown embodied in connection with a dental furnace, though obviously it may be employed with furnaces or heating means of any kind or character.

The invention consists in the matters hereinafter described, and more fully pointed out and defined in the appended claims.

In the drawings, Figure 1 is a top plan view of a dental furnace provided with regulating and controlling means embodying my invention. Fig. 2 is a front elevation of the same. Fig. 3 is a front elevation of a hydrocarbon or gas furnace provided with controlling means embodying my invention. Fig. 4 is a top plan view of the same. Fig. 5 is a front elevation, partly broken, of an electrical furnace, showing a slightly-modified controlling mechanism. Fig. 6 is a similar view showing electrically-operated means for releasing the actuating means.

As shown in said drawings, referring to Figs. 1 and 2, A indicates an electrical furnace such as used by dentists or any preferred kind, the heat of which is increased or diminished in the usual manner by a rheostat, the contact-lever of which is indicated by B and extends for some distance beyond the contact-points b b' b'' on the base a of the furnace and upon which is engaged a spring b^3 , which acts to draw said contact-lever normally out of engagement with said contacts and upon a neutral support b^4 , also secured on said furnace-base. Said furnace-base is secured on a slab A' , of any suitable material, upon which is a clock or other timing device C, which may be of any desired construction or form and upon which in the present instance is a minute-hand C' . Rigidly secured on said minute-hand at its axis is a disk c , having a raised peripheral rim c' , extending partly around the same, as shown in Fig. 1, and affording an open space in its side adjacent the furnace, and in the open space between the ends of said flange or rim is provided a stoppin c^2 , projecting above said disk or plate and adapted to engage a segment c^3 , which is secured upon the shaft for said minute-hand on the side opposite the furnace and is movable with said hand, but adjustable with respect thereto by means of said pin c^4 . The radius of said segment is such as to permit the contact-lever B to rest upon the first contact-point b , as shown in Fig. 1, when the ex-

tremity of said lever rests on the periphery of the segment. Said segment at its rear end is provided with a notch c^6 , which is so positioned that when the segment revolves from beneath the end of the lever B the lever under the influence of the spring b^3 is drawn into said notch or step, which is so positioned that said rheostat-lever then rests upon the contact b' , thus gradually increasing the heat of the furnace until said lever end engages the rim or flange c' on the plate c , at which time said lever engages the contact b^2 , affording the maximum heat of the furnace, and remains on said contact until the minute-hand moves sufficiently to permit the end of the lever to be drawn past the end of said flange or rim c' to a neutral position. This of course immediately cuts off the current and the furnace cools. It is desirable that the heating of the furnace be timed from the moment a certain standard internal temperature is reached. For this purpose thermostatic means are provided for starting the clock or timing device. As shown, a lever D' is pivoted on a standard d' on the base a of the furnace and projects inwardly through the case of the clock into position to engage the end of the lever d of the escapement D at the limit of its movement in one direction. At the other end of said lever beneath the furnace is provided a small receptacle or cup d^3 , which is positioned beneath a vertical passage d^4 , extending through the side of the furnace, and into which projects a pin d^5 of platinum or other refractory metal.

In operating said device a pellet of metal d^6 , having a fusing-point corresponding with the temperature at which it is desired to start the timing of said furnace, is dropped into said tube or passage and rests upon said pin d^5 . When the heat of the furnace has reached a temperature to melt said pellet, the metal drops through into the cup d^3 , overbalancing the lever and releasing the escapement. The heat is then successively increased as the rheostat-lever successively engages the remaining contacts, as before described, and is held constant at the maximum temperature of the furnace for a length of time dependent upon the adjustment of the minute-hand.

The construction shown in Fig. 5 is substantially identical with that indicated in Figs. 1 and 2, with the exception that the timing mechanism or clock is shown in an upright position instead of horizontally and the escapement-lever d is held from movement by means of a lever d^7 , pivoted on the side of the clock-frame. This lever is connected by means of a spring d^8 with a wire or rod d^9 , one end of which projects into the tube d^4 of the furnace A and engages upon a

hook or projection d^{10} therein and is released therefrom when the heat of the furnace becomes sufficient to melt or soften the end of said wire or rod.

In the construction illustrated in Fig. 6 the furnace and clock are constructed as shown in Fig. 5, and, as shown, an electromagnet E is supported on the frame of the clock and the armature e thereof is provided with a spring e' , which normally holds the same in position to engage a lever d of the escapement at one limit of its movement. As shown, a cup e^1 is provided beneath the tube d^4 at the side of the furnace and adapted to receive the melted metal therefrom, which completes the circuit of the battery E through contacts e^2 e^3 , which project above the cup, so that the magnet acts to draw the armature out of engagement with the escapement-lever d , permitting the clock to start.

In the gas or hydrocarbon furnace illustrated in Figs. 3 and 4 the furnace may be of any desired type. As shown, it comprises a muffle A², provided with a burner of any desired type, to which hydrocarbon fluid is admitted through a valve F. A lever f is secured to the valve-stem f², and a spiral spring f¹ engages said lever and a fixed part of the device and acts when the lever is released to close the valve. The end of said lever f when the valve is fully open is engaged beneath the shorter end of the lever F', the other extremity of which when in operative position rests on the periphery of a segment C², carried on the minute-hand C³ of the clock. This clock is started by any suitable thermostatic means. As shown, however, a pellet of metal d⁶, such as before described, is melted and in falling actuates the releasing-lever D'. The valve remains in an open position until the end of the lever F' is released from the segment, after which the valve is immediately closed by the action of said spring f¹. Should it be desired, the heat may be gradually increased to a maximum in the hydrocarbon-furnace as well as the electric, and for this purpose a cam C⁴ is pivoted concentrically with the segment and is provided with a set-screw c¹⁰, whereby the same can be adjusted to the desired point on the segment for operating the valve. Said cam, as shown, is provided with an inclined outer face which terminates at the front edge thereof and the periphery of the segment. In setting the instrument the cam C⁴ is adjusted with the point of the same on the periphery corresponding with the number of minutes it is desired the furnace to operate at maximum heat. When the pellet of metal melts and drops into the receptacle or cup d³, carried on the lever D', as before described, the escapement is liberated, and the end of the lever F',

which is sprung laterally into engagement with the cam C^4 , is elevated by said cam gradually until reaching the periphery of the segment it engages thereon. The upward movement of the end of the lever F' forces the valve-lever f downwardly and opens the valve to its greatest extent and holding the valve fully open until the lever slips from the end of the segment, whereupon the valve immediately is closed by the action of the spring.

The operation is as above set forth in any of the constructions described. When the furnace becomes heated sufficiently to operate the thermostat, the clock which has previously been adjusted to operate for the length of time it is desired to apply heat to the object treated is started. The heat may be progressively increased, decreased, or may remain constant, dependent on the shape of the segments, until shut off by the movement of the timing means, releasing the controlling-lever.

Obviously any desired or suitable means may be employed for starting the clock at the desired temperature of the furnace and any desired or suitable timing mechanism or device may be used. So, too, regulating mechanism embodying my invention may be applied to furnaces and heating means of any desired type or preferred construction adaptable to any desired purposes. I therefore do not purpose limiting this application for patent otherwise than as necessitated by the prior art, as obviously many details of construction and application may be varied without departing from the principles of my invention.

I claim as my invention—

1. The combination with heating means of timing mechanism connected therewith, means acting normally to lock the timing mechanism from movement, thermostatic means acting to release said lock at a predetermined temperature and means acting to successively increase the heat to a predetermined temperature and then cut it off.

2. The combination with heating means of timing mechanism controlled thereby, adjustable means acting normally to lock the timing mechanism from movement, means acting to release the same at a predetermined temperature and start the timing mechanism, a controlling-lever on the heating means and a segment on the timing mechanism acting to operate said lever to regulate the heat.

3. The combination with heating means of timing mechanism connected therewith, locking means acting normally to prevent the timing mechanism from movement, thermostatic means acting to release said lock at a predetermined temperature, means acting to

hold the heating means at said temperature for a given time, and then successively increase the temperature to a maximum.

65

4. In a device of the class described the combination with a furnace of a thermostatically-released clock connected therewith, a heat-controlling lever on said furnace and means on the clock acting to operate said lever to increase the heat of the furnace at successive intervals.

70

5. In a device of the class described the combination with a furnace of a clock connected therewith, a pivoted lever normally engaging the escapement of the clock to prevent the clock from movement, fusible means carried on the furnace and adapted to operate the lever at a predetermined temperature and start the clock, an operating-lever on the furnace and means on the clock acting to successively operate said lever to increase the heat of the furnace.

75

6. The combination with a furnace of a clock connected therewith, an adjustably-weighted lever adapted to normally lock the clock from movement, thermostatically-operated means acting to raise said lever and start the clock, a controlling-lever on the furnace, a segment operated by the clock and adapted to permit the controlling-lever to successively move to increase the heat and means for shutting off the heat at the limit of movement of said lever.

80

7. In a device of the class described the combination with a furnace of a clock connected therewith, a lever adapted to normally hold the clock from movement, fusible means carried in the furnace, a spring connecting the same with said lever and adapted at a predetermined temperature to start the clock, an operative lever on the furnace, a notched segment on the clock in engagement with the operating-lever and a spring acting to successively draw said lever into the notches in said segment and increase the heat of the furnace.

85

8. The combination with a furnace, of a heat-regulating lever thereon, an escapement, clock mechanism, a segment thereon movable with a hand thereof and against which said lever rests in starting the furnace, means normally locking the escapement from movement and a thermostat acting at a predetermined heat to release said escapement.

90

9. The combination with a furnace of the class described, of mechanism connected therewith, thermostatically acting to limit the operation of the furnace to a predetermined interval of time and coacting means on said furnace and timing mechanism whereby said mechanism acts to gradually increase the degree of heat from an initial lower temperature at which the timing mech-

115

120

anism starts to a predetermined higher temperature.

10. In a device of the class described the combination with a furnace of a timing mechanism connected therewith, means adapted to normally lock the timing mechanism from movement thermostatically-operated means acting to release said lock at a predetermined temperature, a plurality of electric contacts to an operating-lever on said furnace adapted

to engage said contacts and means for shifting the lever to successive contacts and acting to successively increase the temperature.

In witness whereof I have hereunto subscribed my name in the presence of two subscribing witnesses.
